US00D819626S

(12) **United States Design Patent** (10) **Patent No.:** **US D819,626 S**
(45) **Date of Patent:** **** Jun. 5, 2018**

(54) **WEARABLE DEVICE**

(71) Applicant: **HUAWEI TECHNOLOGIES CO., LTD.**, Shenzhen (CN)

(72) Inventor: **Xudong Wang**, Shenzhen (CN)

(73) Assignee: **Huawei Technologies Co., Ltd.** (CN)

(**) Term: **15 Years**

(21) Appl. No.: **29/549,947**

(22) Filed: **Dec. 29, 2015**

(30) **Foreign Application Priority Data**

Jul. 3, 2015 (CN) 2015 3 0234010

(51) **LOC (11) Cl.** **14-02**

(52) **U.S. Cl.**

USPC **D14/344**

(58) **Field of Classification Search**

USPC ..... D14/344, 138 R, 144, 358; D24/167, D24/169, 186-187; D11/3, 93-94; D10/30-39, 70, 98; 379/433.1; 361/679.03

CPC G06F 1/163; G06F 1/1628; G06F 1/1626; G06F 1/1635; G06F 1/08; G06F 1/10; G06F 1/04; G06F 1/14; G06F 1/3203; A41D 1/002; H04M 1/02; H04M 1/03; H04M 1/04; H04M 1/05; H04M 1/667; H04M 1/6058; Y02B 60/12; H04B 1/385; H04B 1/3888; H04B 1/3833; G06Q 20/10; G06Q 20/108; G06Q 20/12; G06Q 20/145

(57) **CLAIM**

The ornamental design for a wearable device, as shown and described.

DESCRIPTION

FIG. 1 is a perspective view of a wearable device showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dash-dot lines in the figures and the areas within the dash-dot lines show portions of the wearable device that form no part of the claimed design.

1 Claim, 7 Drawing Sheets
